PICTURE FRAME

Filed July 10, 1930

Carlos Bremer Inventor

By his Attorney
George C. Heimrich

UNITED STATES PATENT OFFICE

CARLOS BREMER, OF BUENOS AIRES, ARGENTINA

PICTURE FRAME

Application filed July 10, 1930, Serial No. 466,982, and in Argentina May 5, 1930.

This invention relates to improvements in picture frames, the rods and other elements of which may be mounted and dismounted at will, providing a very practical and easy

5 system of assembling the frame.

It is well known that the average person, who does not possess more than the minimum of manual ability, experiences some difficulty if he desires to make a picture frame, inasmuch as the ordinary wooden frames are beyond the reach of the majority, and the gummed tapes or ribbons to make the framed glasses, so much in vogue at the present time, also always require a certain amount of

10 ability, even though the advertisements may state the contrary, because on moistening them to adhere to the border of the glass and cardboard, the twisting of the tape occurs, an inconvenience which cannot always be overcome, and this necessitates moistening another piece. Moreover, no matter how well the tape may be adhered, the dampness will with time disjoin it, and the frame will have to be made anew.

25 The present improvements obviate all these inconveniences, inasmuch as they refer to rods, preferably metallic, which anyone can cut with simple scissors and assemble, without requiring great ability or experience as

30 regards exactitude, the adjusting corners being sufficient to conceal any lack of exactitude.

In order that my invention may be clearly comprehensible, I have illustrated same with

35 various figures, wherein:

Fig. 1 is a front view of a rod;

Fig. 2 is a front view of the back part of a corner member; Fig. 2^a is a side view thereof.

40 Fig. 3 is a front and side view of the suspension ring;

Fig. 4 is a side view of the suspension ring inserted and doubled for the desired inclination;

45 Fig. 5 is a front view of a detail of a corner;

Fig. 6 is a front view showing the position of the rods; and

Fig. 7 is a front view of the assembled frame.

Construction

50

These improvements comprise three essential parts; the first a rod *a*, (Fig. 1), the second an adjusting corner *b*, (Fig. 5), and the third the suspension ring *c*, (Figs. 3 and 4). 55

The rod *a* (Fig. 1), is made of sheet metal and doubled in the manner shown in Fig. 1, so that the curve which its fold produces will receive the glass, figure, and cardboard back usual to every picture. These rods *a* can be manufactured in every size and length in order that they may be sold by any measure, in addition to the ease with which they may be cut at any desired point by the person using them.

60 The second part is the adjusting corner *b* (Fig. 5), made from a sheet of the same material as the rod *a* in the following manner: The front of the adjusting corner *b* (Fig. 5),

70 may be of triangular or any other convenient form, with wing members *b*¹ doubled backwards in order that their points will form a right angle, the wing members remaining in the form shown in Fig. 2. These wings *b*¹ have a small groove *d* or inclination, or moulding, or any suitable embossment, and in said groove a number of perforations *e* are made in such manner that they form an interior projection. By the use of the word projection in connection with the perforations *e*, it is meant to indicate the small rough projections which remain on one side of a sheet of metal in which perforations have been made, a typical case in point being that of a grater.

80 The third part of these improvements is constituted by a suspension ring *c* (Figs. 3 and 4). It comprises a common ring *c*, which is held by a clasp *c*¹, the latter enclosing the ring *c* at its upper part, and is made in such 85

80

85

90

a manner that it forms two sections, one longer than the other (Fig. 3).

The material employed in the execution of the parts described will preferably be metal, although celluloid, galalith, and any other material adaptable to the object in view, may be employed. In the same manner, both the rods *a* and adjusting corners *b* will not only be plain as shown in the attached drawings, but may also bear every class of stamping of high or bass relief, including mouldings, etc., of any type, and may be of any colour, tone and system of ornamentation, graphic decoration and embellishment which may be desired, and may be of all sizes, without this meaning a departure from the sphere of the present invention.

Assembly of the frame

20 The principal characteristic of the present improvements is the ease with which the frame is made and assembled, even by persons completely lacking in manual ability.

Previously the glass *v* will have been cut to size, as also the picture or figure which it is desired to frame, the details of which are shown in Fig. 5 indicated with the letter *f*, together with the cardboard back *r*, also shown in detail in Fig. 5. These three parts 30 having been cut, the clasp *c*¹ of the ring is placed in a more or less high position and midway in the cardboard back *r*, and its point will be doubled in an upward direction (Fig. 4), and the shorter part bears a fold *j* at 35 one end, in order that on being opened more or less, an angle of greater or less inclination of the picture is obtained (Fig. 4), in which figure the clasp *c*¹ is shown having penetrated in the cardboard *r* and doubled in an upward direction, and its shorter length forms an inclined angle, as has been stated.

On this cardboard back *r* is placed the picture *f*, generally of cardboard or pasteboard, and on the picture *f* the glass *v*. The 45 conjunct having been obtained, two lengths of the rod are cut, the longer *a*, Fig. 6, being the vertical rods, and the conjunct is made to enter into same, the fold *a*¹ of the rods being calculated to effect a slight pressure. The 50 horizontal rods *a* (Fig. 6) are then cut and are placed the same as the vertical ones, it being found better to always cut them a little less, as indicated in Fig. 6. The four rods *a*, having been placed in position, it is necessary to secure them together, which is done 55 by means of the adjusting corners *b*. The groove *d* of these corners (Fig. 2) bears some perforations *e* with projections, which hold the fold *a*¹ of the rods *a*, and with this end 60 in view the width of said fold *a*¹ and the position of the perforations *e* (Fig. 2) have been calculated. Once the four adjusting corners have been placed in position, the dismounting 65 of the frame is not possible, unless the wing members *b*¹ are raised sufficiently to

avoid their biting the projections of the perforations *e* and withdrawing them from their position.

Having thus described my invention, what I claim as new, and desire to secure by Letters Patent, is:

In a picture frame including its long and short channel bars forming the frame for the reception of glass, picture and cardboard backing, corner pieces to hold the channel bars together, each of said corner pieces comprising a substantially triangularly shaped body, triangular wing members formed with two sides of said body and bent upon the same and having grooves formed therein, tongues formed in the bottom of the grooves by perforating the material thereof, and adapted to engage the channels of the frame bars.

In testimony whereof, I affix my signature.

CARLOS BREMER.
